UNITED STATES PATENT OFFICE.

FRANK A. HALLECK, OF OAK PARK, ILLINOIS, ASSIGNEE TO SULLIVAN MACHINERY COMPANY, A CORPORATION OF MASSACHUSETTS.

FORGING MACHINE.

Application filed May 2, 1919. Serial No. 294,268.

This invention relates to forging machines and more particularly though not exclusively to that type of forging machine used for sharpening drill steels and other tools and implements.

One object of the present invention is to provide an improved forging machine. Another object is to provide an improved forging machine wherein all the necessary operating tools are conveniently mounted on a single base and are so arranged and operated that an operator may easily work a steel or other instrument to the required shape. Still another object of the present invention is to provide an improved construction wherein all the parts are easily accessible and operable and such that all moving parts are automatically lubricated. These and other objects and advantages of my improved construction will, however, hereinafter more fully appear.

In the accompanying drawings, I have shown for purposes of illustration one embodiment which my invention may assume in practice.

In these drawings—

Fig. 1 is a longitudinal sectional view of my improved forging machine, parts thereof being shown in side elevation.

Fig. 2 is a front elevation thereof.

Fig. 3 is a plan view thereof.

Fig. 4 is a detail side elevation of a part of the mechanism as indicated by the line 4—4 Fig. 3.

Fig. 5 is a detail side elevation taken substantially as indicated at 5—5 Fig. 2.

Fig. 6 is a longitudinal sectional view of the side swaging hammer, parts thereof being shown in side elevation.

Fig. 7 is a detail rear elevation of a part of my improved mechanism substantially as indicated by line 7—7 Fig. 1, parts of the mechanism being removed to facilitate the illustration.

In this illustrative construction, I have shown a hollow base 1 carrying adjacent one side thereof a side swaging tool 2 having a striking pin 2', the latter being adapted to strike the upper of two swaging blocks 3, 4.

To eliminate in so far as possible projecting members, I preferably pass the inlet pipe 5 from the upper end of the tool through a supporting arm 6 into the hollow interior of the base 1, the fluid flow from this pipe being controlled by a cut-off valve, not

shown, the latter being controlled by a conveniently-located lever 5'.

The pneumatic tool may be of any type desired but for purposes of illustration, there is shown only the inlet 5 and the exhaust passage 6', the latter having communication with the forward end of the cylinder through an exhaust port 7. The exhaust passage preferably communicates with the hollow interior of the base through a passageway 8 formed in the supporting arm 6, this passage also having a port 9 through which exhaust fluid is delivered to the work to blow the scale and dust therefrom.

The upper die block 3 is preferably formed separate from the striking pin 2' and is preferably normally held in an elevated position free from the work or the lower die block 4 by a plurality of springs 10, the inner ends of which are bent inwardly and projected into oppositely disposed holes 11 in this die block, the opposite ends of the springs being, in the form shown herein, coiled about a shaft 12 and attached thereto as by having the ends thereof inserted into holes in the shaft 12. A spring tension controlling handle 13 is also attached to the shaft 12 as by a pin 14, this handle carrying

also a transversely projecting lug 15 which may be caught under a lug 16 attached to the supporting arm 6 in which the shaft 12 is rotatably mounted. If it is desired to change or inspect the upper die block, the

springs may be freed from the same by depressing the handle 13 and moving the latter to the right to free the lug 15 from the lug 16 when the handle 13 may be elevated to decrease the spring tension and permit an easy withdrawal of the bent ends of the

springs from the holes 11 in the opposite faces of the die block 3. When it is desired to replace the die block 3, the same is inserted into its guide in the arm 6, the ends of the springs are inserted in the holes 11, the lever 13 is depressed and moved transversely of the supporting arm until the lugs engage to hold the springs under tension.

In my preferred form of construction, the tension of the springs is sufficient to retain not only the movable die block, but also the piston and striking pin in an elevated position.

I also provide an improved means for detachably securing the lower die block 4 on

the lever 13, this lever being controlled by a conveniently-located lever 5'.

I also provide an improved means for detachably securing the lower die block 4 on

the base 1 and for this purpose I provide an anvil block 17 detachably secured in a suitable recess 17' of the base by a bolt 18 passing through an upper face of the base and having a head 19 formed thereon and seated in a socket 20 in the upper face of the anvil, the lower end of this bolt carrying an adjusting nut 21 which receives the thrust of one end of a coiled spring 22 abutting 10 against the base 1 and compressed between it and the nut 21 on the bolt. The lower part of the fixed die block 4 has a dovetail section 23 securely held between a mating dovetail section of the anvil block, a part 24 15 of which is formed integral with the block, the remainder 25 being separate from the block and being clamped thereto by a bolt 26 and being held in correct position by a pin 27 preferably formed integral with the 20 clamping member 25 and projecting into a hole formed in the casting or base 1. By this improved construction any wear of the anvil block incident to the operation of the swaging hammer is automatically taken up 25 by the spring 22 and the tension of the latter is easily varied by movement of the adjusting nut 21 to which access may be had through an opening 22' in the front face of the base 1. The lower die block may be 30 easily changed by freeing the clamping member 25 through a movement of the retaining nut or bolt 26 or if the lower die block wears through the operation of the swaging hammer this wear may be easily taken up by 35 a tightening of the bolt 26.

It should be noted that by this improved construction of the swaging members, all parts thereof are simply and easily constructed, that the parts are easily disassembled for inspection or repair, that these parts are automatically held in their proper operative positions, and that an adjustment of the parts is easily made from the exterior of the forging machine.

I also provide in my improved forging device a work clamping means shown herein as comprising a fixed jaw 28' on a cross head 28 extending substantially across the machine and a movable jaw 29' shown herein as mounted on a cross head 29 of similar dimensions, the upper and movable cross head being operated by a pair of standards 30 united at their lower ends by a cross head 31. The mechanism for operating the lower yoke 31 and thereby the upper vise jaw preferably consists of a toggle joint mechanism comprising two links 32, 33, the first of which is pivoted at one end 31' thereof to the cross head 31, the other end of this link being pivoted as shown at 32' to a link actuating member 34. The link 33 is preferably pivoted as shown at 35 to the first link intermediate the ends thereof and to the base 1 of the forging machine as shown at 36, the link 33 being preferably recessed as shown 40 at 37 to receive the pivot 32' in order that when the reciprocating member 34 is moved to the right, the pivots 31', 35, and 36 may be substantially in alinement. Since the greatest force is exerted by a toggle mechanism of this character at the moment when the pivot 35 is crossing a line joining the pivots 31' and 36, the construction above described permits the utilizing of the maximum force of the toggle for gripping a steel 45 or other instrument between the two vise jaws and it should be noted that because the pivot 36 is placed above the pivot 32' thereby lengthening the link 33, the maximum efficiency is obtained through the use of this 50 relatively long link.

The reciprocating element 34 which actuates the toggle mechanism directly may be actuated by any means desired, but in the form shown herein, I provide two opposite 55 pistons 38, 39 having oppositely disposed pressure surfaces 40 and 41, the pressure surface 40 being always subject to fluid pressure in the cylinder 42 to which pressure fluid is conducted by a pipe line 43. Pressure fluid is only admitted to the larger cylinder 44 to act on the larger piston head 41 to move the reciprocating member 34 to the right against a pressure exerted on the surface 40, when it is desired to clamp a 60 steel between the jaws. The flow of pressure fluid to the cylinder 44 and to the cylinder 53 is controlled by a valve mechanism 45, the valve mechanism having communication with the cylinder 44 through a port 100 46 and being controlled by any suitable means such as lever 47. The exhaust from the valve chest 45 may, if desired, be directed into the atmosphere but I preferably direct this exhaust as through a passageway 48 105 (see Fig. 7) into the hollow interior of the base and also through suitable passageways 49, 50, and 51 to recesses 52 surrounding the standards 30 in order that the standards 110 may be automatically lubricated by the lubricant carried by the pressure fluid. From the foregoing, it will be obvious that when the lever 47 is depressed pressure fluid will flow into the large cylinder 44 to operate the toggle mechanism and that through the improved construction of the toggle mechanism, a maximum force will be delivered to 115 the upper cross head 29.

The upsetting mechanism for upsetting the end of a tool held between the vise jaws is shown herein as having a cylinder 53 to which pressure fluid is conducted through a pipe 54, the exhaust from this cylinder preferably being conducted by an exhaust passage 55 to the interior of the base 1. Reciprocatively mounted within this cylinder 53 is a piston 56 adapted to strike a striking pin 57 and force the latter against a dolly 58, the latter being held in a proper position by a dolly guide, the upper section or cover 120 125 130

59 of which is preferably adjustable in position to facilitate the insertion or withdrawal of the tool. As shown, this dolly guide cover 59 is pivotally connected at 60 to the supporting member which guides the striking pin, the guide having also a reinforcing web 61 herein shown as extending along the sides and front thereof. During the operation of the upsetting member, this 10 guide is preferably held in operative position as shown in Fig. 1 by resilient mechanism carried by the movable cross head 29, this mechanism in the form shown herein comprising a bolt 62 having on one end thereof a head 63 so formed as to receive a portion of the reinforcing flange 61, and a spring 64 abutting against this head and a boss 65 carried by the cross head. When the upper cross head is elevated, the head 63 is moved out of contact with the cover 59 a sufficient distance to permit the swinging of the cover on its pivot 60, but when the cover is swung downward to properly guide the dolly and the cross head is lowered into its 25 lowest position, the head 63 engages the cover and retains the latter in its proper operating position.

The exhaust pressure fluid from the upsetting hammer and the larger cylinder 44 passes into a large chamber 66 from which the oil laden exhaust fluid is distributed through a plurality of ports 67, 68, 69 to different parts such as the toggle mechanism and the mechanism for holding the anvil 30 block in place to lubricate these parts. To prevent the greater part of the lubricant from flowing to but one of these parts, such as to the toggle mechanism through the passage 67, a boss 67' is provided which forms the sump in the lower part of the chamber 66 to catch the surplus oil which would otherwise drain to this passageway. As will be apparent, during the inoperative periods of the forging machine or when the swaging hammer alone is being used, any oil 45 which has collected in this sump will slowly evaporate and will be distributed throughout the base and the parts in communication therewith to lubricate these parts, prevent their rusting, and keep them in good working order.

In the operation of the forging machine on hollow tools such as hollow drill steels, it is often necessary to enlarge the hollow opening in the end of the steel which may become partially closed through the operation of the upsetting and swaging hammers on the end of the steel and for this purpose I provide a pinning tool 70 preferably carried adjacent one end of the lower cross head 28, this pinning tool having a pin or punch 71 which is driven by the pinning tool into the end of the steel to enlarge the opening therein. It will be understood that 50 the pinning tool 70 is a pneumatic motor having a piston therein, not shown, adapted upon its forward strokes to actuate the pin 71, the pin accordingly being driven into a hole in a hollow steel by a rapid series of blows. As this pin or punch tends to stick 55 in the end of the tool during the pinning operation, I preferably provide a means for retaining the pin in operative relation to the pinning tool and, as is best shown in Figs. 2, 3, and 4, this retaining means has a 60 yoke 72 which straddles the pin and is engageable with a collar or projection 71' formed thereon to prevent the removal of the pin, this yoke being preferably pivotally connected as by a pivot 73 to a forwardly 65 projecting portion 74 of a plate 75 fastened as by bolts 76 to the cross head 28. During the pinning operation, if the pin should stick in the bore of the tool, the latter may be jerked rearwardly to free the pin from the tool, but the pin will not thereby be removed from the pinning tool. However, if it is desired to replace the tool, the yoke 72 may be sprung upward out of the way and the pin may be easily withdrawn.

In the operation of modern forging machines, and especially of those adapted to forge drilling steels, it is necessary to vary the gage of the steel and for this purpose, I provide a variable gaging means comprising cooperating elements 77, 78 carried by the movable and fixed cross heads respectively. The gaging element 77, whose transverse curvature may be readily observed from Fig. 2, is preferably fixed in the movable cross head, and the gaging element 78, whose gaging portion proper is invisible, is preferably adjustable, and is held in its adjusted positions by means of a plate 79. By adjusting the relative position of the gaging element 78 with reference to the gaging element 77, it is possible to thereby vary the gage of a tool which may be finished between these gaging elements. The general structure of this mechanism is disclosed in my co-pending application Ser. No. 179,952, filed July 11, 1917, and now Patent No. 1,461,011, July 3, 1923, the structure here illustrated differing from that of my aforesaid patent only by reason of the fact that 75 the adjusting plate and member are turned into a substantially horizontal plane instead of being disposed as in my aforesaid patent.

Formed preferably on the ends of the cross heads adjacent the pinning tool is a pair of vise jaws, 80, 81 which may be used to grip a tool when it is desired to perform operations on the tool by hand or by other instrument than those mounted on the forging machine, the very ends 82 of these vise jaws being formed as shearing elements to cut off or remove portions of stock.

In order to facilitate the cleansing of the dies and the different parts of the forging machine, I provide also a flexible tube 83

having a nozzle 84 formed on one end thereof the opposite end of the tube being preferably attached to the inlet side of the valve box 45 so that fluid pressure is constantly supplied to this tube. Inasmuch as the operator performs all the operations on the forging machine while standing at the front end thereof, I preferably provide a means for retaining the nozzle 84 adjacent the front end of the forging machine, this means in the present embodiment of my invention comprising a yoke 85 fastened on the top of the swaging hammer 2.

The fluid pressure utilized throughout the forging machine is admitted to the different mechanisms from an inlet pipe 86, the pressure fluid being preferably supplied with the proper amount of lubricant by a lubricating device 87, before the pressure fluid flows to any of the working parts of the forging machine.

It will thus be seen that I have provided a relatively light, compact, and small forging machine which performs all the operations necessary for the forging of hollow or solid tools, and that the operating mechanisms and the tools therefor are so located that the operator can perform all the required operations while standing in practically one position in front of the forging machine. It will further be noted that all the parts of the forging machine are readily accessible for inspection or repair, that the parts are easily disassembled, and that all the parts are automatically retained in adjusted position. It will further be noted that all moving parts are amply and automatically lubricated and that it is only necessary for the operator to keep the oiling mechanism supplied with lubricant to insure the parts against rusting or other deterioration when the machine is left idle.

While I have in this application specifically described one embodiment which my invention may assume in practice, it is to be understood that this form is used for illustrative purposes only and that the invention may be modified and embodied in various other forms without departing from its spirit or the scope of the appended claims.

What I claim as new and desire to secure by Letters Patent is:

1. In a forging machine, a tool, a movable die operated thereby, an anvil die disposed in alinement with the path of movement of said other die, and means for normally insuring that the first mentioned die will take a given position with respect to the anvil die including means for exerting a force on said first mentioned die and means cooperating therewith for varying the force exerted by said force exerting means upon said first mentioned die.

2. In a forging machine, a die, actuating mechanism therefor separate therefrom, a

cooperating die, said dies being adapted to effect a forging operation while having a substantially immovable relation, means for normally maintaining said first die in a given position including means exerting a force thereon, and means for varying the force exerted on said die by said first mentioned means while all of said elements have a normal operative relation.

3. In a forging machine, a die and actuating mechanism therefor, a cooperating die, said dies being adapted to effect a forging operation while having a substantially immovable relation, means for automatically exerting a force on said first mentioned die for returning said die to a given position, and means normally manually operable adapted to cooperate therewith for varying the force exerted by said other means upon said die.

4. In a forging machine, a die, actuating means therefor, a cooperating fixed anvil die, resilient means for returning said first mentioned die to a given position after it has been moved away from such position, and manual means for controlling said resilient means cooperating directly therewith.

5. In a forging machine, a tool of the hammer type, a movable die operated thereby, an anvil die disposed in alinement with the path of movement of said other die, means for exerting a force on said first mentioned die for normally maintaining the first mentioned die in spaced relation to said anvil die, whereby a work piece may be inserted between them, and means cooperating with said first mentioned means for varying the force which said first mentioned means exerts upon said first mentioned die.

6. In a forging machine, a tool, a die operated thereby, an anvil die, said dies being adapted to have a substantially fixed relation to each other during a forging operation, detachable means for exerting a force on said first mentioned die for normally returning the first mentioned die to a given position with respect to the anvil die, and means cooperating therewith for varying the force exerted by said first mentioned means upon said first mentioned die.

7. In a forging machine, a tool, a movable die operated thereby, an anvil die disposed in alinement with the path of movement of said other die, detachable means for exerting a force on said first mentioned die for normally automatically maintaining the first mentioned die in predetermined space relation to said anvil die, whereby a work piece may be inserted between them, and means cooperating therewith for varying the force exerted by said first mentioned means upon said first mentioned die.

8. In a forging machine, a tool, a movable die operated thereby, an anvil die disposed in alinement with the path of move-

- ment of said other die, detachable means for exerting a force on said first mentioned die for normally maintaining the first mentioned die in spaced relation to said anvil die, whereby a work piece may be inserted between them, and means for varying the force which said first mentioned means exerts upon said first mentioned die, said last mentioned means being operable to relieve the force exerted by said first mentioned means to facilitate detaching the latter from the die. 10
9. In a forging machine, a tool, a die operated thereby, an anvil die, spring means for normally automatically maintaining the first mentioned die in predetermined spaced relation to said anvil die, whereby a work piece may be inserted between them, and manually operable means cooperating therewith for varying the force exerted by said 15 spring means upon said first mentioned die. 20
10. In a forging machine, an anvil die, a tool, a die operated thereby, a plurality of means for exerting a force on said last mentioned die for normally automatically retaining said last mentioned die in predetermined spaced position relative to said anvil die, and a single manually operable means for varying the force exerted by said plurality of retaining means, said manually 25 operable means having only a single operative connection to said retaining means. 30
11. In a forging machine, a fixed anvil die, a tool, a die operated by said tool, a plurality of springs under compression for normally retaining said second mentioned die in spaced relation to said anvil die, and a single manually operable means for relieving the compression to which said springs are subjected whereby said second mentioned 35 die may approach said anvil die. 40
12. In a forging machine, a tool, a die operated thereby, a cooperating fixed anvil die, resilient means for normally retaining said first mentioned die in one position, and a single means releasably maintaining the 45 resilient means in position to retain said die in such position. 50
13. In a forging machine, a die, a cooperating fixed anvil die, resilient means for normally retaining said first mentioned die in a single position, and manual means for releasably maintaining said resilient means in position to retain said die in such position. 55
14. In a forging machine, a die, resilient means disposed on the side thereof for normally retaining the same in a given position, and a manually operable lever associated with said resilient means adapted to release said die from the influence of said resilient 60 means. 65
15. In a forging machine, a die, a cooperating fixed anvil die, resilient means for automatically returning said first mentioned die to a single position during operation thereon, and manual means associated 70 with and adapted to release said resilient means to free said first mentioned die from its control. 75
16. In a forging machine, a die, a cooperating fixed anvil die, a manually operable member, and resilient means connected to said die and member and normally tending to hold said die in one position during operation thereof but movable to release the 80 same therefrom. 85
17. In a forging machine, a member, supporting means therefor, and yieldable means normally tending to hold said member in a single position and adapted to yieldably force said member to a released position. 90
18. In a forging machine, a member, and manually controlled yieldable means normally tending to hold said member in a single position and adapted to yieldably force said member to a released position, said means including a laterally and longitudinally movable lever. 95
19. In a forging machine, a die member, a cooperating fixed die, and manually controlled yieldable means tending to hold said member in a single position during operation thereof, said means including manual grasping means. 100
20. In a forging machine, a die member, yieldable means tending to hold said member in a single position during operation thereof, and a manually operable pivoted lever adapted to tension said yieldable means. 105
21. In a forging machine, a perforated base, an anvil block thereon, a tension member connected at one end to said block and disposed with its axis perpendicular to the work supporting face of said block at substantially the center thereof, and passing at its other end through a hole in said base, and spring means acting on said last mentioned end and placing said member under tension, said tension member causing said block to abut against said base. 110
22. In a forging machine, a perforated base, an anvil block resting thereupon, a tension member connected at one end to said block and disposed with its axis perpendicular to the work supporting face of said block at substantially the center thereof, and passing at its other end through a hole in said base, spring means acting on said last mentioned end and placing said member under tension, and means for adjusting the tension exerted by said spring. 115
23. In a forging machine, a tool, a movable die operated thereby, an anvil die disposed in alinement with the path of movement of said other die, means for exerting a force on said first mentioned die for normally maintaining the first mentioned die in a given position with respect to the anvil die, and means including a pivotal member cooperating therewith for varying the force 120 125 130

exerted by said first mentioned means upon said first mentioned die.

24. In a forging machine, a tool, a movable die operated thereby, an anvil die disposed in alinement with the path of movement of said other die, means for exerting a force on said first mentioned die for normally maintaining the first mentioned die in a given position with respect to the anvil die, and means including a member slidale for adjustment whereby the same may be held or released during cooperation of said latter means with said other means so that the force exerted by said first mentioned means upon said first mentioned die will be varied.

25. In a forging machine, a tool, a movable die operated thereby, an anvil die disposed in the path of movement of said other die, means for exerting a force on said first mentioned die for normally maintaining the first mentioned die in a given position with respect to the anvil die, means cooperating therewith for varying the force exerted by said first mentioned means upon said first mentioned die, and a common member adapted to have operative connection with both of said means.

In testimony whereof I affix my signature.

FRANK A. HALLECK.
